UNITED STATES PATENT OFFICE.

ROBERT M. DIXON, OF EAST ORANGE, NEW JERSEY, ASSIGNOR TO SAFETY CAR HEATING AND LIGHTING COMPANY, A CORPORATION OF NEW JERSEY.

DESIGN FOR A REFLECTOR FOR LIGHT-FIXTURES.

47,642.

Specification for Design.

Patented July 27, 1915.

Application filed April 17, 1914. Serial No. 832,649. Term of patent 7 years.

To all whom it may concern:

Be it known that I, ROBERT M. DIXON, a citizen of the United States, residing at East Orange, county of Essex, and State of New Jersey, have invented a new, original, and ornamental Design for a Reflector for Light-Fixtures, of which the following is a specification, reference being had to the accompanying drawing, forming part thereof.

Figure 1 is a sectional elevation showing the shape of my new reflector; and Fig. 2 is a bottom plan of said reflector.

I claim:

The ornamental design for a reflector for light fixtures, as shown.

In testimony whereof I have hereunto signed my name in the presence of two subscribing witnesses.

ROBERT M. DIXON.
